(No Model.)

N. A. FISHER.

MECHANISM FOR MOVING STREET CARS ON CURVES.

No. 315,491.

Patented Apr. 14, 1885.

UNITED STATES PATENT OFFICE.

NOBLE ANDREW FISHER, OF SACRAMENTO, CALIFORNIA.

MECHANISM FOR MOVING STREET-CARS ON CURVES.

SPECIFICATION forming part of Letters Patent No. 315,491, dated April 14, 1885.

Application filed February 2, 1884. (No model.)

To all whom it may concern:

Be it known that I, NOBLE ANDREW FISHER, a citizen of the United States, residing at Sacramento, in the county of Sacramento, State of California, have invented certain new and useful Improvements in the Process or Mechanism for Moving Street-Cars on Curves, as patented to me by Letters Patent of the United States dated December 11, 1883, and numbered 289,904, as more fully hereinafter specified.

My invention relates to a cable railway, and particularly to the construction of the longitudinal way through which the cable passes; and the novelty consists in the arrangement and adaptation of parts, as will be more fully hereinafter set forth, and specifically pointed out in the claims. In such roads or railways the cable always bears against the rollers upon the side toward which the curvature tends, and when the clutch arrives at the first roller of the hinged section the cable is forced away from those rollers, and the deflection of the cable extends for a considerable distance down the straight line. This deflection of the cable is caused by the fact that the clutch has to pass between it and the rollers arranged at the commencement of the curve. I provide that the cable way shall have a hinged section at the commencement of the curve, the rollers upon which section shall, when the section is in a normal position, hold the cable in proper line. Upon the approach of a car, and at a time when otherwise the clutch would be forced between the cable and stationary rollers, I provide that this hinged portion shall turn on its pivot sufficiently to allow the clutch to pass without deflecting the cable—in other words, that they shall automatically move to one side and allow the clutch to pass. I provide that as soon as the clutch has passed this portion of the way the said hinged portion shall again automatically reassume its normal position to properly support the cable in line. I provide that both these movements shall be accomplished automatically by the passing car.

For purposes of this description it will be assumed that the cable passes in a gutter between the tracks, and this gutter is provided upon either side and bottom with anti-friction rollers. Upon a curve the rollers are only necessary upon the inner side of the curve.

The clamp which engages the cable is carried about centrally upon the car. The cable is moved by suitable power, and the cars partake of the motion of the cable as the clamps upon the car engage and hold the cable.

The invention is illustrated in the accompanying drawings, which form a part of this specification, and in which Figure 1 is a plan view of a cable way, showing a portion of a curve adjoining a straight line, the hinged section being understood to be the commencement of the curve. Fig. 2 is a perspective view showing the hinged section and the mechanism for operating it, the said section being represented in the position which it assumes when a car is passing after having acted upon roller *d*. Fig. 3 is a perspective view of a section of the way, taken at the pivotal portion of the movable section, and showing the mechanism for restoring the pivoted or movable section to its normal position. Fig. 4 is a detail showing the relation of important parts when the movable section is in normal position.

Referring to the drawings, *A* designates a portion of a cable-way having horizontal rollers *b* and vertical rollers *a*. These parts are of any well-known construction, except that I provide that the section which comprises the first part of the curve, and which is designated by the letter *B*, is hinged or pivoted to the stationary part, as seen at *C*, Fig. 1.

M designates a vertical frame, in which is journaled a rock-shaft, *D*, and this rock-shaft carries a rigid arm, *e*, with a friction-roller, *d*, in its upper end, held in the path of a projecting portion of the car. An arm, *a*, rigid upon this rock-shaft *D*, is connected by a link, *D'*, with one arm of an elbow-lever, *M*, the other arm being pivoted to a vertically-sliding post, *F*, having an inclined portion, *f*. The elbow-lever *M* is suitably pivoted at the junction of its two arms to any proper stationary object, and the slide *F* has vertical movement in proper guides, *G*.

A spring, *E*, secured at one end to a stationary staple, *c*, and at the other to the arm *e*, serves with a constant force, through the rock-shaft *D*, link *D'*, and elbow-lever *M*, to hold the slide *F* in its lowest position, as seen in Fig. 2. The hinged section has a roller, *I*, journaled upon its free end, and this roller is

arranged to traverse the face of the slide F, resting upon the vertical face, when the movable section has moved away to allow the passage of the clutch, and upon the incline f^5 5 when the movable section is in its normal position, supporting the cable.

Journalized in a suitable stationary frame near the free end of the movable section is a rock-shaft, D, having a rigid arm, e, which 10 carries a roller, d, and projects up into the path of some portion of the passing car. This rock-shaft carries an arm, g, which, by a link, f, is connected to an elbow-lever, H, pivoted at a proper stationary point, as shown. The 15 other arm of this lever carries a pin, e', which, when the slide F is in a normal position, engages a socket, e'', therein, and serves to hold the slide in its elevated position. A spring, E, serves to hold this pin into connection with the slide with a constant force, and when the 20 pin and slide are engaged the parts assume the position seen in Fig. 4—that is to say, with the roller I resting upon the incline f^5 . When in this position, the rollers a support 25 the cable as the movable section B is forced away from the vertical plane of the slide F.

The operation of the device is obvious. The standard or arm e is so arranged that it will be engaged by some projecting portion of the 30 passing car at the moment when the clutch is approaching the free end of the movable section in the direction indicated by the arrows. As the rock-shaft D is oscillated by the depression of the arm e, the pin e' is withdrawn 35 from its socket e'', and the movable section turns on its pivot by reason of the tension of the cable, the roller I bearing against the incline f^5 of the slide, and the clutch passes the first rollers of the movable section without 40 deflection, and consequently without deflecting the cable along the straight line of track. As soon as the clutch has passed its depth around the curvature of the section B, the car strikes and depresses the arm e', which action, through 45 the connections described, forces up the slide

F, when its incline f^5 will engage the roller I during the movement of the former, until the movable section again assumes a normal position with its free end supporting the cable.

Having thus described my invention, what I 50 claim as new, and desire to secure by Letters Patent, is—

1. A railway having a plate provided with a hinged apron or section to prevent deflection of the rope or cable, substantially as specified. 55

2. The combination, with a railway having a plate provided with a hinged section to prevent deflection of the rope or cable, of an inclined slide-bearing and means for operating 60 the same to move the hinged section, substantially as specified.

3. The combination, with the plate adapted to move laterally, of a vertically-inclined slide-bearing, angle-lever carrying a pin for engaging the slide-bearing, and means for operating 65 the same, substantially as specified.

4. The combination, with the hinged section or apron, of the vertically-inclined slide-bearing engaging the same, a transverse rock-shaft having a vertical spring-arm, and intermediate devices for inserting and withdrawing the pin of the angle-lever from the slide-bearing, substantially as specified. 70

5. The combination, with the plate having 75 a hinged section, of a rock-shaft having a fixed vertical arm provided with a spring, devices for connecting the said rock-shaft to a vertical slide-bearing, and a rock-shaft having a similar arm, and devices connecting with the rock-shaft for locking and unlocking the slide-bearing, substantially as specified. 80

6. The plate having its hinged section provided with a roller adapted to engage a vertical inclined slide-bearing, substantially as 85 specified.

NOBLE ANDREW FISHER.
